UNITED STATES PATENT OFFICE.

GEORGE H. HELVEY, OF HAMILTON, OHIO, ASSIGNOR TO THE HOOVEN,
OWENS & RENTSCHLER COMPANY, OF SAME PLACE.

JOURNAL-BEARING.

SPECIFICATION forming part of Letters Patent No. 380,035, dated March 27, 1888.

Application filed September 27, 1887. Serial No. 250,864. (No model.)

To all whom it may concern:

Be it known that I, GEORGE H. HELVEY, of Hamilton, Butler county, Ohio, have invented certain new and useful Improvements 5 in Journal-Bearings, of which the following is a specification.

This invention pertains to journal-bearings applicable with a special advantage to the main bearings of pillow-blocks of steam-engines.

10 My improvement will be readily understood from the following description, taken in connection with the accompanying drawings, in which—

Figure 1 is a side elevation of the pillow-block end of the bed-piece of a horizontal steam-engine, the pillow-block being illustrated as forming the termination of the girder-bed A, the engine-shaft in this view appearing in transverse section; Fig. 2, a vertical section through the pillow-block at right angles to the plane of Fig. 1, the collar on the shaft appearing also in vertical section; Fig. 3, a side elevation of the removable shaft-collar; Fig. 4, an edge view of this collar.

25 In the drawings, A represents the end portion of the girder-bed of a horizontal steam-engine, being that portion of the bed which adjoins the main bearing or pillow-block; B, the pedestal of the pillow-block, the same being attached or formed with the portion A of the bed-plate and provided with feet to serve 30 in attaching it to its foundation; C, an upwardly-open rectangular recess in the top of the pedestal to receive the bearing portions of the pillow-block; D, the usual quarter-box seated on the floor of this recess, one at each side of the shaft, and to be provided, preferably, with means by which they may be adjusted inwardly as wear takes place, such 35 means commonly consisting of vertically-moving wedges disposed between the backs of the quarter-box and the inner face of the pedestal-jaws, and arranged to be adjusted by studs and nuts projecting above the pillow-block cap; 40

45 E, a rectangular recess in the pedestal below the floor of the recess C, the recess E lying directly below the shaft; F, a bed-box fitting the recess E and extending from side to side of the pedestal, this bed-box forming the bottom 50 bearing for the shaft; G, the shaft; H, the cap

of the pillow-block, secured to the pedestal, as usual, and serving as the top bearing of the pillow-block; J, a shallow groove in the periphery of the shaft just beyond the rear side face of the pillow-block; K, a collar firmly secured to the shaft at this groove, the collar seating in the bottom of the groove, such collar being divided and joined by screws, as shown in Figs. 3 and 4, so as to permit its ready attachment to and removal from the shaft; L, a representation in dotted line of the bed-box F in process of being withdrawn from its normal position, and M a screw-eye or handle to be temporarily inserted into a suitable hole in the end of the bed-box to serve as a means for withdrawing it from its normal position.

In steam-engines of the larger class and having crank-shafts with a diameter of twelve inches and over, and of corresponding weight, 70 great difficulty is experienced in keeping the main bearing in proper order. Engines of this size are generally employed in situations where continuous operation is of the utmost importance, and long delays, incident to repairs, &c., of the pillow-block, become serious. As pillow-blocks are generally constructed, it becomes necessary in effecting repairs or substitution of the bed-box to disconnect the connecting-rod of the engine from the crank and 75 to elevate the crank-shaft well or entirely out of the pillow-block; and in cases where the engine-shaft is long or coupled direct to succeeding lengths of shaft it becomes necessary to disconnect the shaft at such coupling, so as 80 to permit the proper elevation of shaft to be made at the pillow-block end, it being necessary, under such circumstances, that the shaft should rise in the outboard-box, as well as in the pillow-block at the crank end. Operations 85 such as this involve long stoppages of the engine and require a great deal of labor and the presence of quite a number of workmen.

The procedure with my improvement is as follows: The collar K is removed in an obvious manner. The bolts securing the cap H are then loosened considerably. A jack-screw is then placed under the crank, and the crank and crank end of the shaft are elevated a mere trifle, or the elevating may be effected by 90

means of blocks and wedges under the crank. The screw-eye M, or a similar handle, is then attached to the exposed end of the bed-box, and the bed-box is drawn longitudinally and 5 angularly outward, as indicated in Fig. 2. A new bed-box in good condition may be at once inserted, or the one removed may be relined and restored, after which the shaft is lowered, the collar restored to its place, and the cap 10 again adjusted. All of this work may be done by one man and in an exceedingly short space of time. No disconnections of the connecting-rod or of the shaft-couplings are called for, and even the pillow-block cap need not be removed. 15 In case a mere vertical adjustment of the bed-box is desired, instead of a relining or a substitution, a shim of proper thickness is to be laid upon the floor of the recess E before the bed-box is restored. The sides of the 20 recess E are to be parallel with each other and at right angles to the floor of that recess,

and the bed-box is to fit that recess as snugly as is consistent with ready removal and insertion of the bed-box in the manner described.

I claim as my invention—

In a pillow-block, the combination of a pedestal provided with a rectangular recess below the shaft, quarter-boxes secured in the pedestal, a cap for the pedestal, a bed-box set in said rectangular recess and fitted for longitudinal withdrawal therefrom, a shaft supported by the pillow-block, and a collar secured to said shaft against the end of said bed-box and serving to prevent the endwise displacement of said bed-box, and fitted for removal therefrom to permit the endwise withdrawal of the bed-box, substantially as and for the purpose set forth.

GEO. H. HELVEY.
